UNITED STATES PATENT OFFICE

2,074,972

INTERNAL-COMBUSTION ENGINE CYLINDER-HEAD CONSTRUCTION

Ralph L. Skinner, Detroit, Mich.

Application December 23, 1935, Serial No. 55,775

12 Claims. (Cl. 123—75)

The present invention concerns betterments in the heads of the cylinders of internal-combustion engines and in their manner of mounting on or in the cylinders, one of the leading aims of the 5 invention being to provide a construction in which the head is yieldingly mounted on or in its cylinder, so that the shocks imposed on the head by reason of the gas pressures in the cylinder are cushioned and are transmitted only in part 10 through the head to the cylinder, thus rendering possible an engine which has smoother operating characteristics than has heretofore been obtainable for similar engines.

Another feature of the construction aiding in 15 the accomplishment of the stated object is the making of the head itself somewhat resilient or elastic to dissipate some of the pressure concussions.

To permit those acquainted with this art to 20 understand the invention and its advantages, both from structural and functional standpoints, a present, preferred embodiment of the invention has been illustrated in detail in the accompanying drawing, the single view of which represents a 25 central, longitudinal section through a portion of an engine embodying the invention, the engine being of the general type presented in United States Patent No. 1,830,136, Ralph L. Skinner, Internal-combustion engine, granted November 3, 30 1931, to which patent reference is made for an understanding of the generic construction and mode of operation of the engine.

By reference to this drawing, some of the parts 35 of the structure are an outer, ported engine-cylinder 11, a shorter, unported, inner engine-cylinder or liner 12 in, and spaced inwardly away from, the exterior cylinder 11, a piston 13 reciprocable in the inner cylinder or liner, a pair of arcuate valves 14 and 15 slidable longitudinally between the two cylinders and reciprocated by means not 40 shown, a split, elastic, expansible and contractible, ported sealing-ring 16 bearing at one end on the end of the inner cylinder, and a continuous hold-down ring 17 pressing against the opposite end of the sealing-ring and having an inwardly-extended flange 18 along its lower edge subjected to the 45 gaseous pressure in the cylinder, the structure including also the several parts or elements hereinafter described.

50 A hollow, round cylinder-head or end-closure 19 has (a) a top, outwardly-projecting, marginal flange 21 entirely encased in a rubber shield or cover 22, preferably vulcanized thereto and of the desired or required degree of resiliency or elasticity; (b) an exterior sloping or conical surface

23 connecting with one end of (c) an outer cylindrical surface 24; (d) a shoulder or stop 25 at the other end of the cylindrical part 24; (e) another external, reduced-diameter, cylindrical surface 26 extending inwardly of the outer cylinder 11 to (f) a corrugated, somewhat-flexible, round end-wall 27 apertured eccentrically to the axes of the two engine-cylinders 11 and 12 for the accommodation of the reduced-diameter end-portion of a tubular well-member 28 having a 10 screw-threaded opening through its inner, lower end housing a spark-plug 29.

A plurality of thin, nested, metallic, conical, flexible, upwardly-sloping, cylinder-head guiding and centering reeds 31 are confined against the similarly-shaped surface or shoulder 23 by an appropriately-formed collar 32 having a tight, sliding fit on the larger, cylindrical surface 24 of the head.

A somewhat-conical-shaped ring-spring 33 bears against the under or inner surface of the collar 32 and overlies and presses downwardly or inwardly the hold-down ring 17 to maintain the ported sealing-ring 16 properly on its seat on the end of the inner cylinder 12.

A sleeve or collar 34 has a binding or frictional fit on the surface 26 of the head and bears at one 20 end against the shoulder 25 which properly and correctly positions it, such member 34 having a downwardly, outwardly, sloping surface 35 bearing against and holding in place a number of nested, metallic, conical, downwardly-outwardly-sloping, flexible, ring reeds 36 against a complementary, inclined surface of a collar 37 bearing at its other end against a shoulder or upset projections 38 at the end of sleeve 34.

The outer edges of these resilient or elastic 30 reeds are ground to fit and to press against the inner face of the adjacent hold-down ring 17, all as is clearly illustrated.

Obviously, when the gas pressure in the outer 40 engine-cylinder 11 is imposed on the underside of the protruding or exposed portion of these reeds 36, the latter bend or yield upwardly slightly, thus increasing their diameter in minor degree and in this manner maintaining a pressure-tight relation with the hold-down ring 17, assuring the prevention of the escape of any of the gas past such reeds.

The cylinder-head and its associated parts, constructed as described, is held in place on and in the cylinder by a ring 41 shaped to house the rubber covering 22 and bearing directly on the top of the cylinder-block at 42, being held in place by the usual studs 43 and nuts 44.

From what precedes, it will be clear that the cylinder-head makes no direct contact with the cylinder-block except through the rubber 22 and the flexible reeds 34 and 36, these three elastic elements constituting cushions and minimizing the transmission of the shocks, received by the cylinder-head from the explosions in its cylinder, to the cylinder-casting, thus materially reducing the noise incident to the operation of the engine and assuring a smooth action thereof, this advantage being aided and facilitated by reason of the fact that the somewhat-flexible end 27 of the cylinder-head absorbs some of the concussions.

15 In addition, the cylinder-head is provided with a suitably-shaped cover 51 held on the cylinder-block in any approved manner, as by screws 52, with an appropriate gasket 53 between itself and the block, this gasket, if desired, being of rubber.

20 In order to sound-insulate the upper part of the spark-plug well-member 28 which extends up through an opening in the cover 51, the margin of such aperture is formed to accommodate a rubber ring 54 through which the element 28 extends with the rubber in liquid-tight contact with it.

25 Internally and secured to it, the cover has a centrally-apertured partition or division wall 55 with a deflector-skirt 56 in register with its aperture and reaching nearly to the bottom of the interior of the cylinder-head.

30 The specified construction, therefore, provides two communicating chambers 57 and 58 on opposite sides of the walls 55, 56, cooling water, by means not shown, being fed into one such chamber and delivered or discharged from the other.

35 From what has been stated above, it will be apparent that the tubular, spark-plug-housing member 28 is sound insulated from the cover and the latter more or less from the cylinder-casting, so that the advantage accruing in sound insulation of the head from the cylinder-block is not neutralized or overcome either wholly or in part by sound-transmission through the element 28.

40 45 As has been indicated above, reeds 36 are ground to fit the hold-down ring and, in many instances, it is desirable to similarly grind the reeds 34 to fit the outer cylinder.

50 The three parts 34, 36, and 37, when combined or associated together in the manner shown, form a single assembly which can be readily ground or sized to fit the cylinder-head and the hold-down ring before such assembly is applied or pressed on to the head in the relation shown.

55 60 The eccentric or off-center mounting of the spark-plug in the head, the flexibility of a part of the head itself, the insulation or cushioning of the head, and the insulation of the spark-plug well-member, all contribute their share to the even and quiet running of the engine, in that they unitedly absorb or cushion the vibrations and pressures to which they are intermittently exposed or reduce the transmission of the forces 65 to the cylinder-block.

65 70 Although rubber and metallic reed cushioning means have been referred to, those skilled in the art will readily understand that other appropriate materials may be used.

70 75 The invention is not limited to the precise and exact details of structure shown, because these may be modified within more or less radical limits without departure from the heart and essence of the invention as defined by the appended claims and without the loss or sacrifice of

any of the material benefits or advantages accruing from the employment of the invention.

It is to be noted also that, by eccentrically positioning the spark-plug, a substantial benefit is attained in that the force of the explosion does not reach all parts of the outer cylinder at the same time, but rather such shock or sudden pressure rise is imposed on the different transverse parts of the inner surface of the cylinder and its associated members progressively or non-concurrently, hence aiding in the smooth and substantially noiseless operation of the engine.

I claim:

1. In an internal-combustion engine, the combination of an engine-cylinder, a piston reciprocable in said cylinder, a head for said cylinder mounted thereon, and means completely resiliently separating said head from said cylinder, whereby to cushion the forces to which said head is subjected.

2. The structure presented in claim 1 in which said resilient means comprises metallic reeds and non-metallic means.

3. The structure presented in claim 1 in which said cylinder-head extends into said cylinder and in which said resilient means includes metallic reed means between the cylinder and the portion of said head in the cylinder and non-metallic means between the upper portion of the cylinder and the head.

4. In an internal-combustion engine, the combination of an outer ported cylinder, an inner cylinder inside of said outer cylinder and spaced from the latter, reciprocable ported valve-means between said cylinders, an expansible ported sealing-ring bearing at one end on an end of said inner cylinder, a hold-down ring bearing endwise on the other end of said sealing-ring, means pressing said hold-down ring toward said sealing-ring, a head for and extended part way into said outer cylinder, means mounting said head on said outer cylinder, resilient pressure-confining means on said head bearing on the inner surface of said hold-down ring, and resilient guiding-means on said head bearing against the inner surface of said outer cylinder.

5. The construction presented in claim 4 in which said means mounting said head on said outer cylinder includes resilient means completely cushioning said head from said outer cylinder.

6. The construction presented in claim 4 in which said resilient pressure-confining means consists of nested flexible reeds sloping outwardly from said head and inwardly of said outer cylinder and in which said resilient guiding-means consists of nested flexible reeds sloping outwardly from said head and outwardly with relation to said outer cylinder.

7. In an internal-combustion engine, the combination of an engine-cylinder, a piston reciprocable in said cylinder, a head mounted on said cylinder, resilient means completely cushioning said head from said cylinder, a spark-plug well-member on said head, a cover for said head, and resilient means cushioning said well-member from said cover.

8. In an internal-combustion engine, the combination of an outer ported cylinder, an inner cylinder inside of said outer cylinder and spaced from the latter, reciprocable ported valve-means between said cylinders, an expansible ported sealing-ring bearing at one end on an end of said inner cylinder, a hold-down ring bearing endwise on the other end of said sealing-ring, means pressing said hold-down ring toward

- said scaling-ring, a head for and extended part-way into said outer cylinder, resilient pressure-confining means on said head bearing on the inner surface of said hold-down ring, resilient guiding-means on said head bearing against the inner surface of said outer cylinder, means fastening said head to said outer cylinder, and resilient cushioning means between said head, cylinder and fastening means. 5
- 10 9. The structure presented in claim 8 in which said resilient pressure-confining means consists of nested flexible reeds sloping outwardly from the head and inwardly of said outer cylinder and in which said resilient guiding-means consists 15 of nested flexible reeds sloping outwardly from said head and outwardly with relation to said outer cylinder and in which said resilient cushioning means between said head, cylinder and fastening means is composed of rubber.
- 20 10. The structure presented in claim 1 in which said cylinder-head extends into said cylinder and in which said resilient separating means includes resilient means between the portion of said head in said cylinder and said cylinder and resilient means between that portion of said head outside of said cylinder and said cylinder. 5
11. In an internal-combustion engine, the combination of an engine-cylinder, a head for said cylinder having a flange, means for fastening said flange to said engine-cylinder, and resilient means completely cushioning said fastening means from said flange and said flange from said cylinder. 10
12. In an internal-combustion engine, the combination of an engine-cylinder, a head for said cylinder having a flange and extending inside of said cylinder, means for fastening said flange to said engine-cylinder, resilient means completely cushioning said fastening means from said flange and said flange from said cylinder, and resilient means cushioning that portion of said cylinder-head in said cylinder from said cylinder. 15 20
